UNITED STATES PATENT OFFICE.

ZYGMUNT PEHEL, OF NEW YORK, N. Y., ASSIGNOR OF ONE-HALF TO JULIAN STRZYCKOWSKI, OF NEW YORK, N. Y.

AUTOMATIC LOCK FOR WINDOWS.

1,298,251.

Specification of Letters Patent.

Patented Mar. 25, 1919.

Application filed November 10, 1916. Serial No. 130,521.

To all whom it may concern:

Be it known that I, ZYGMUNT PEHEL, a subject of the Czar of Russia, and a resident of Bronx and county of Bronx and State of New York, have invented certain new and useful Improvements in Automatic Locks for Windows, of which the following is a specification.

This invention relates to improvements in means for securing the sashes of ordinary windows in a locked position, one relative to the other, and its principal object is to provide means which may be operated from the interior, positively locking one of the window sashes with the other, and having means combined which tend to draw the two sashes toward each other.

A further object is to provide such devices in forms which are inexpensive to manufacture, readily applied to window sashes of ordinary construction, and which may be operated by any person without previous experience.

These and like objects are attained by the novel construction and combination of parts hereafter described and shown in the accompanying drawings, forming a material part of this specification, and in which:—

Figure 1 is a partial vertical sectional view showing a pair of sashes in an unlocked position.

Fig. 2 is a similar view of the same showing the sashes in a locked or engaged position.

Fig. 3 is an enlarged fragmental sectional view showing the same construction as that disclosed in Fig. 2.

Fig. 4 is a transverse sectional view taken on line 4—4 of Fig. 3.

Fig. 5 is a similar transverse sectional view taken on line 5—5 of Fig. 3, but showing the bolt retracted, and

Fig. 6 is a side elevational view showing the device as it appears when applied to the window sash, parts being removed to show the construction.

In Figs. 1 and 2, the lower portion of a complete window frame is shown containing the lower member 11 of the upper outer sash, the corresponding lower element 12 of the lower inner sash resting upon the sill 10 in the usual manner, the disposition being so that the upper element 14 of the lower sash is positioned closely adjacent to the sash 11, when the windows are in a closed position,

and in order to lock the same against movement when in such position an opening 15 is formed in the lower member of the upper sash element, the opening being covered by a plate 16, held to the sash by means of the screws 17, the plate being provided with an elongated rectangular aperture 18 leading directly to the recess 15.

In the upper element 14 of the inner sash is a through opening 20 having on the inner side an enlarged or counterbored portion 21 in which is rigidly affixed an annular casing 22 provided with a flanged base 23 from which extends a cylindrical sleeve 24, the flange being secured by screws 25, and surrounding the sleeve 24 is a tubular element 28 attached to a hollow stem 29 which extends outwardly beyond the sash, and is provided with a disk 30 at its head by means of which the sleeve 28 may be drawn outwardly through the bushing 31, having a flange 32 secured by screws 33 to the lower sash.

Engaged rigidly within the tubular sleeve 29 and held to the head 30 by the screw 35, is a bolt 36 slidable within the sleeve 24 and provided with a T shaped head 38 adapted to pass through the opening 18 in the plate 16, and to be turned therein by manipulating the disk 30, thereby engaging at the rear side with the plate 16 in such manner as to prevent its being withdrawn except the disk 30 be further turned.

In addition, a coiled spring 39 surrounds the bolt 36 and exerts pressure between the end of the sleeve 24 and the shoulder formed within the hollow stem 29, the spring tending to press the disk 30 outwardly and at the same time to exert a considerable tension upon the elongated rectangular bolt head 38, causing the sash elements to be drawn firmly together, thereby avoiding the passage of air or the like, and binding the two sashes so that neither one can be moved without the disk be turned to free the bolt.

The construction, application, and use will be evident from the foregoing description and drawings which disclose an effective device for the purpose mentioned.

Having thus described my invention, what I claim as new, and desire to secure by Letters Patent, is:—

In a device as described, in combination, a window sash having an opening through one side thereof and having an enlarged portion at the opposite side thereof, an annular cas-

- ing fitting snugly in said enlarged portion of said opening and having a cylindrical sleeve projecting concentrically into said opening, said casing being secured against displacement from said sash, a tubular element snugly and slidably fitting said opening and telescoping over said sleeve, said element having a reduced hollow stem, a bolt projecting into said sleeve and into said hollow stem, a disk formed upon the outer end of said stem, providing a handle and secured to said bolt, a spring coiled around said bolt, fitting said tubular element and

bearing respectively against the inner edges of said sleeve and reduced stem, and a T-shaped head formed terminally upon said bolt, said spring normally disposing said head within said casing and spacing said disk outwardly from said sash, and coöperating locking means upon an adjacent sash 15 20 adapted to be engaged by the T-shaped head on the bolt.

Signed at New York, in the county of New York, and State of New York, this 30th day of October, 1916.

ZYGMUNT PEHEL.

Copies of this patent may be obtained for five cents each, by addressing the "Commissioner of Patents, Washington, D. C."
